UNITED STATES PATENT OFFICE.

WILLIAM MUELLER, OF ST. LOUIS, MISSOURI.

COMBINED PROPELLER AND STEERER.

SPECIFICATION forming part of Letters Patent No. 462,572, dated November 3, 1891.

Application filed May 20, 1891. Serial No. 393,477. (No model.)

To all whom it may concern:

Be it known that I, WILLIAM MUELLER, of the city of St. Louis and State of Missouri, have invented certain new and useful Improvements in a Combined Boat Propeller and Steerer, of which the following is a full, clear, and exact description, reference being had to the accompanying drawings, forming a part hereof.

10 My invention relates to improvements in combined boat propellers and steerers; and it consists in the novel arrangement and combination of parts, as will be more fully hereinafter described, and designated in the 15 claims.

In the drawings, Figure 1 is a side elevation of my complete invention as applied to a boat. Fig. 2 is a vertical longitudinal section of the same. Fig. 3 is a cross-section 20 taken on the line $x-x$ of Fig. 2. Fig. 4 is a perspective view of the mechanism which supports the gearing mechanism. Fig. 5 is a top plan view of the mechanism which holds my invention to the keel of a boat. Fig. 6 is 25 a perspective view of the mechanism by which my invention is adjusted to and from the boat. Fig. 7 is an enlarged vertical section of the gearing mechanism itself, through the agency of which motion is communicated or 30 imparted to the propeller. Fig. 8 is a similar section of the bevel-gear mechanism which I employ in carrying out my invention. Fig. 9 is a top plan view of one of the gear-wheels with the plate removed, showing the interior 35 mechanism; and Fig. 10 is a top plan view of a detached or removed plate.

The object of my invention is to construct a device preferably to be attached to the rear portion of a boat for propelling and steering 40 the same, thereby dispensing with oars and lateral mechanism, which has heretofore been employed for effecting said result and purpose. By this construction of a propeller and steerer my invention is made more adaptable 45 to propel boats in subterranean passages.

With these preliminary statements relative to the object and purpose of my invention, I will now proceed to describe the same in detail.

50 Referring to the drawings, 1 indicates the boat itself, which embodies the ordinary con-

struction, and 2 indicates the propeller, which embodies the construction as illustrated in the drawings. However I do not wish to limit myself to the specific construction of 55 the propeller as illustrated. Said propeller 2 is mounted in any suitable and mechanical manner on horizontal shaft 3, the same being similarly mounted in a frame-work 4. Adjustably mounted on shaft 3 is a bevel-gear- 60 pinion 5, the same adapted to engage and mesh with a similarly-constructed bevel-pin- 65 ion 6, which is adjustably mounted on a vertical operating-shaft 7, the same being pro- 70 vided with a longitudinal groove 8, for the 75 purpose hereinafter set forth.

The mechanism just described is supported upon a right-angular bar 9, the same being so constructed that it may be adjusted in a vertical direction through the agency of the 70 mechanism hereinafter described. The ob- 75 ject of this vertical adjustment is to make the propeller 2 susceptible of perfect and easy operation in shallow and deep water. It can also be readily perceived from this construc- 80 tion that the propeller 2, or, in other words, the mechanism which supports said propeller, may be elevated or lowered in water of dif- 85 ferent depths. It can also be readily per- 90 ceived by the construction, as I will now de- 95 scribe, that the propeller may be adjusted to and from the boat 1. This adjustment is ef- fected by means of a graduated bar 11, one 100 end of which is pivotally secured in any suit- able and mechanical manner to the vertical bar 10, and the opposite end of the same is adapted to pass through a peculiarly-shaped supporting device 12, as illustrated in Fig. 6. Said bar 11 is provided with depressions 13, in which a catch 14, secured to device 12, is 105 adapted to engage, thereby holding the bar 11 in the proper adjustment.

Pivotally secured to device 12 in any suit- 110 able and mechanical manner is a U-shaped bar 15, the same adapted to snugly fit over 115 keel 16 of boat 1, the function of which is to 120 hold device 12 in a suitable adjustment rela- tive to the other coacting mechanism.

The vertical operating-bar 7 is suitably 125 mounted in a sleeve 17, (referring to Fig. 2,) 130 which sleeve is concentrically placed in an outer sleeve 18, the function of which mech-

anism will be more fully hereinafter described. Bar 10 is provided with a groove, or rather with an U-shaped socket, in which bar 9 is adapted to loosely fit, thereby permitting the latter to be vertically adjusted in said groove; the proper adjustment of same being retained by means of a thumb-screw 19. Sleeve 18 is adjustably or, rather, rotatably mounted on frame-work 20. It may be premised in this connection that the bevel-gear 6 is rigidly mounted on shaft 7, as can readily be perceived by referring to Fig. 2. It will also be readily perceived from the construction as hereinafter set forth that propeller 2 15 may be laterally adjusted, thereby effecting the proper steerage of the boat. This lateral adjustment of propeller 2 is effected by means of a worm-pinion 21, mounted upon shaft 7, and a worm 22, adapted to engage 20 with said pinion, the latter being actuated by the operator located in the boat.

The worm which engages with the worm-pinion 21 is formed upon a shaft on which a wheel 23 is mounted in any suitable and mechanical manner. Said wheel is provided with projections 24, which make the same susceptible of being operated by means of a chain 25, said chain 25 being first rotated or moved by means of a similar wheel 26, the 30 same being mounted upon the boat in any suitable and mechanical manner, and also being provided with cranks 27. It may be premised in this connection that the bevel-pinion 21 is rigidly mounted in any suitable and mechanical manner to the outer sleeve 18, and consequently when said pinion is rotated the propeller and the system of bevel-gears which operate the same are also turned in a lateral direction, by which the proper 35 steerage of the boat is effected. In other words, if the operator desires to steer the boat 1 it is only necessary for him to turn wheel 26 and the coacting mechanism connected with the same will effect the proper steering. 40 It may be premised in this connection that the frame-work 4 is pivotally mounted on a right angular bar 9. It may be observed in this connection that sleeve 18 is provided with an elongated groove or slot 29, and also mounted upon said sleeve is a collar 30, which said collar is secured to sleeve 17 by means of screws 31, and said screws 31 pass through the elongated slot 29, formed in sleeve 18, and enter the inner sleeve 17. In other words, 45 the inner sleeve 17 may be adjusted in a vertical direction independently of sleeve 18; but by the construction as just described whenever sleeve 17 is rotated sleeve 18 is also simultaneously rotated, premising, however, 50 that a block 32 is secured to screws 31 and is adapted to freely fit in slot or groove 29.

Having described the system of beveled gears which operate the propeller 2, I will now describe in detail the operating-shaft 7 and the mechanism which rotates the same. I will describe in this connection, however, first, the mechanism by which my invention is held

and secured in a proper position to the rear portion of boat 1, which is effected by means of a clamp 33, provided with a thumb-screw 70 34. Clamp 33 is provided with a perforation in which the bar 10 is adapted to fit, thereby preventing the same from turning. The clamp 33 is pivotally secured to arm 35, and said arm is secured to the cross-piece 36, the same 75 being secured to frame-work 56. By this construction my device is equally adapted to be attached to any form of boat.

I will now proceed to describe the mechanism which rotates shaft 7. The mechanism 80 which effects said rotation is located in a frame-work 38, (see Fig. 2,) and said frame-work is held to bar 10 by means of a collar 39. Located in frame-work 38 is a similar frame-work 40, (see Fig. 4,) in which the gear-wheels 85 47 are located. Said frame-work 40 is provided with grooves 41, in which shaft 7 is adapted to fit, and also provided with depressions or grooves 42, in which a vertical guide-bar 43 is adapted to fit. The vertical guide-bar 43 is secured to the frame-work 38. (See Fig. 2.) Pivotally secured to frame-work 40 is an arm 44, and pivotally secured to said arm 44 is a lever 45, one arm of which lever is pivotally secured to an arm 46, secured to frame-work 38, and to the other arm of said lever a wire rope or chain 47' is secured for operating the same. The frame-work 40 is mounted upon a spiral spring 48, which encircles the operating-shaft 7, the function of 90 which spring is to restore the frame-work 40, and consequently the gear-wheels located in same, to their proper or normal position after the same has been once depressed or lowered. Mounted upon the operating-shaft 7 are a series of four gear-wheels 47, of the construction as shown in Fig. 9. Located in said gear-wheels are ratchet-wheels 48, the same being provided in the region of their center with lugs 49, the same adapted to fit in groove 8, 100 formed in the operating-bar 7. Pivotally secured in the region of the circumference of gear-wheels 47 are dogs 50, which permit gear-wheels 47 to move in one direction independently of the ratchet-teeth wheels 48, and when moved in the opposite direction the dogs 50 engage with ratchet-wheels 48, and consequently rotate said ratchet-wheels, and consequently the operating-shaft on which they are mounted. Dogs 50 are actuated by means 110 of springs 51. The gear-wheels 47 have a face-plate 52, the same adapted to be readily detached for inspecting and repairing the inner mechanism should it chance to get out of order.

Having described the construction of the gear-wheels 47, I will now proceed to describe the location of the same on the operating-shaft 7 and the rack-bars which operate and rotate the same.

Fig. 7 illustrates the relative position of the gear-wheels on the operating-shaft 7. 53 and 54 indicate two rack-bars of similar construction which face each other, the ends of which

are connected together by means of bars 55. Bar 54 is located in a plane below bar 53. Said bars are located in a frame-work 56 and are adapted to freely move in a backward and forward direction. Said racks are adapted to engage with the gear-wheels 47. Frame-work 56 is mounted on and secured to cross-piece 36.

Referring to Fig. 7, the two lower gear-wheels are so constructed and located that they propel the boat in a forward direction. In other words, the two lower wheels are an exact fac-simile of the wheel and ratchet-teeth wheel, as illustrated in Fig. 9, and are located on shaft 7, with their detachable faces turned upwardly.

The two upper wheels, as illustrated in Fig. 7, are constructed and adapted to propel the boat in a backward direction, and the ratchet-wheel 48, located in the two upper, have their teeth oppositely formed to the ratchet-wheel in the two lower wheels. The rack-bar 54 engages with the lowest of the gear-wheels and rack-bar 53 engages with the next to the lowest, and whenever said rack-bars are pushed in a backward direction or pulled in a forward direction the two lowest of the gear-wheels 47 move in opposite directions, but are so constructed that one of the said wheels 47 turns the ratchet-teeth wheel located therein, and consequently rotates the operating-shaft 7. For instance, if one of the said two wheels which propel the boat in a forward direction rotates its inclosed ratchet-teeth wheel when the rack-bars are pulled the other one of said wheels will rotate its inclosed ratchet-wheel when the rack-bars are pushed.

The operation of the two upper wheels or those that are adapted to propel the boat in a backward direction is the same as the operation of the two lower wheels, but the difference in construction consists in the inner ratchet-teeth wheels, which are formed oppositely to the two lower wheels. Of course when it is desired to propel the boat in a backward direction the two upper ratchet-teeth wheels are lowered and brought in engagement with the rack-bars 53 and 54 by means of frame-work 40, which is operated by the mechanism hereinbefore described.

The rack-bars 53 and 54 are operated in a forward and rearward direction by means of a handle 58, which may run the entire length of the boat. The handle 58 is pivotally secured in any mechanical manner to the bar 55, which connects the ends of said rack-bars. Said bars may be operated by hand-power, as hereinbefore stated, or by steam-power.

The right-angular bar 9 and the mechanism mounted thereon is lowered and elevated by means of a cord or chain 59, one end of which is attached to said right-angular bar and the other end passes over a pulley and passes to the boat.

It may be further observed that the mechanism which I employ in rotating the verti-

cal operating-shaft 7 may be employed as the motive power in various classes of mechanism.

I do not wish to limit myself to the specific mechanical construction as illustrated and described, nor do I wish to limit myself to the exact location of my invention relative to the boat as described.

Having fully described my invention, what I claim is—

1. In a combined boat propeller and steerer, a vertical rod having an offset lower end pivotally mounted at the stern of the boat, a frame pivoted on said offset portion, a propeller-shaft carrying a propeller mounted therein, a vertical shaft mounted in suitable frame-work and adapted to impart motion to the propeller-shaft, means to actuate said vertical shaft, and a device to operate said propeller-carrying frame, substantially as described. 75

2. In a combined boat propeller and steerer, a vertically-adjustable rod having an offset lower end mounted at the stern of the boat, a frame carrying a propeller pivoted on said offset portion, a vertical shaft to impart motion to the propeller-shaft, means to actuate said vertical shaft, telescopic sleeves surrounding the latter, the lower one being secured to the propeller-carrying frame, and means to actuate the sleeves, whereby said frame and propeller are operated to steer the boat, substantially as described. 90

3. In a combined boat propeller and steerer, a vertically-adjustable rod having an offset lower end mounted at the stern of the boat, a frame carrying a propeller pivoted on said offset portion, a vertical shaft to impart motion to the propeller-shaft, means to actuate said vertical shaft, telescopic sleeves surrounding the latter, the lower end being secured to the propeller-carrying frame, a worm-wheel secured to the upper sleeve, a worm meshing therewith, and means to operate said worm, substantially as described. 100

4. In a combined boat propeller and steerer, a vertically-adjustable rod having an offset lower end mounted at the stern of the boat, a frame 4, pivoted thereon, a horizontal shaft carrying a propeller and a bevel-gear journaled thereon, a vertical shaft carrying a bevel-gear at its lower end meshing with said first-mentioned gear, means to operate said vertical shaft, telescopic sleeves surrounding the latter, one being connected to the frame 115 and the upper one carrying a worm-wheel, a worm meshing with said wheel, and means to operate said worm, substantially as described. 120

5. In a combined boat propeller and steerer, a vertically-adjustable rod having an offset lower end mounted at the stern of the boat, a frame carrying a propeller pivoted on said offset portion, a vertical shaft to impart motion to the propeller-shaft, means to actuate said vertical shaft, telescopic sleeves surrounding the latter, the lower one being secured to the propeller-carrying frame and the 130

upper one carrying a worm-wheel, a worm meshing therewith, a sprocket-wheel on the shaft of said worm, a second sprocket-wheel carrying a crank mounted on the boat, and a 5 chain connecting said wheels, substantially as described.

6. In a device for propelling boats, a clamp 33, a frame-work pivoted thereto, a vertical shaft adapted to drive the propeller-shaft, 10 gear-wheels and ratchet-wheels mounted on said vertical shaft, a reciprocating frame carrying rack-bars engaging with the gear-wheels, and means whereby the motion of said gear-wheels is imparted to the ratchet- 15 wheels and thence to the vertical shaft, substantially as described.

7. In a device for propelling boats, a clamp 33, a frame-work pivoted thereto, a vertical shaft adapted to drive the propeller-shaft, 20 ratchet-wheels vertically adjustable on said shaft but rotating therewith, gear-wheels carrying pawls engaging with the ratchet-wheels, a reciprocating frame carrying rack-bars engaging said gear-wheels, each rack-bar 25 engaging a different wheel, and the ratchet-teeth of each wheel being turned in opposite directions, whereby the forward and backward movement of the frame will drive the vertical shaft in the same direction, substantially as described.

8. In a device for propelling boats, a vertical shaft adapted to drive the propeller-shaft, two series of ratchet-wheels and gear-wheels vertically-adjustable on said first- 30 mentioned shaft, a reciprocating frame carrying rack-bars, and a frame adapted to throw either series of wheels into engagement with the said rack-bars, substantially as described.

9. In a device for propelling boats, a vertical shaft adapted to drive the propeller-shaft, two series of gear-wheels vertically-adjustable on said first-mentioned shaft, the 40 wheels of each series being adapted to impart motion to the shaft when revolved in opposite directions, a frame carrying rack-bars to 45 operate the gear-wheels, a frame 40 inclosing said wheels and adapted to throw either series into engagement with the rack-bars, a spring supporting said frame, a guide on which the frame moves, and means to operate said frame, substantially as described.

10. In a device for propelling boats, a clamp adapted to engage the boat and having an aperture therein, a vertical bar passing therethrough, a frame carrying a propeller 55 carried by said vertical bar, a propeller, mechanism to operate the same, a frame-work carrying said mechanism and pivoted to clamp 33, and an adjustable bar 11, connecting the lower end of the vertical bar which 60 passes through the clamp with the keel of the boat, substantially as described.

11. In a device for propelling boats, a frame-work carrying the operating mechanism, a clamp attached to the boat and to 65 which the said frame-work is pivoted, a vertical bar supported by said clamp and carrying a propeller, and an adjustable bar 11, connecting the lower end of vertical bar with the 70 keel of the boat, substantially as described.

In testimony whereof I affix my signature in presence of two witnesses.

WILLIAM MUELLER.
